UNITED STATES PATENT OFFICE

2,549,718

SCRAPER UNIT FOR ENDLESS MOVING SURFACES

William F. Spang, Milton, Mass., assignor to Cube Steak Machine Co., Needham Heights, Mass., a partnership

Application July 17, 1948, Serial No. 39,360

1 Claim. (Cl. 143—29)

1

This invention relates to a novel cleaning unit for endless moving surfaces such as wheels, band saws, etc. Smooth and efficient running of such apparatus requires that these surfaces which come into cooperating contact shall be kept free from dirt, grit and refuse particles. I am aware that various scrapers have been employed for this purpose but such devices have been operated from a tangential position which has not performed the desired operation efficiently. I have discovered that a cleaning unit disposed substantially normal to the surface to be cleaned will perform the cleaning operation in superior manner and the primary object of my invention resides in the production of an improved unit thus constructed and operated for this purpose.

These and other features of the invention will be best understood and appreciated from the following description of a preferred embodiment thereof selected for purposes of illustration and shown in the accompanying drawings in which:

Fig. 1 illustrates diagrammatically a band saw unit employing my invention.

Fig. 2 is a rear end elevation of my improved surface cleaning unit.

Fig. 3 is a side elevation thereof, partially in section, and

Fig. 4 is a plan elevation, partially in section.

In Fig. 1 I have illustrated a band saw 10 supported on three wheels or rolls 12. The cooperating surfaces of the saw and wheels must be kept free from dirt, grit and the like if the cooperating parts are to function efficiently. The improved unit 14 which I have invented for performing this function is mounted to operate at an angle normal to the surface being cleaned and is provided with a sharp cutting tooth constructed and arranged to function as illustrated and hereinafter described. The unit is adapted to operate on any moving surfaces substantially as illustrated in Fig. 1.

My improved unit 14 embodies a plunger 16 provided with a cutting tooth 18 at its forward end and mounted to slide longitudinally in a supporting block 20. The forward extremity of the tooth 18 terminates in a sharp cutting edge 19. The block 20 is open at its forward end to receive the plunger and its rear end is provided with a hole 22 for receiving the smaller rear end 24 of the plunger. A compression spring 26 normally forces the plunger forwardly and a detent 28 is provided for holding the plunger against rotation. As illustrated in Fig. 2 the forward portion 16 of the plunger is circular in cross section and has a longitudinal key slot therein receiving the re-

duced inner end of the detent 28. It will be apparent that this circular construction of the plunger 16 and the cooperating bore within the block 20 provide a structure that can be produced economically and with great precision. This construction together with the one-piece block 20 provides a strong and superior support for resisting the cutting thrusts against the plunger and provides for quick and easy assembly and disassembly of the unit. The block 20 is supported in a bracket 30 provided with a spring pressed detent 32 for holding it within the bracket.

Each wheel 12 illustrated in the drawing has a saw supporting periphery 33 grooved circumferentially and the cutting extremity 19 of the tooth 18 is formed to fit this grooved surface as shown in Fig. 4. The bracket 30 and block 20 support the plunger 16 for sliding movement normal to the surface to be cleaned. The tooth 18 has a top surface 34 extending rearwardly from the cutting extremity 19 and disposed in a plane substantially normal to the surface 33 and a bottom surface 36 diverging from the top surface from the extremity 19 rearwardly. Thus the tooth 18 provides a sharp cutting edge always held in cutting contact with the surface 33 by the spring 26 and adapted to keep the surface 33 clean of all foreign matter that would interfere with the operation of the machine.

The block 20 can be removed for repair or replacement merely by releasing the detent 32 and the plunger is freely removable forwardly from the block. The invention therefore provides a unit which can be easily removed and replaced and which serves the intended function with maximum efficiency.

Having thus disclosed my invention, I claim as new and desire to secure by Letters Patent:

40 A scraper unit for endless moving surfaces, comprising a one-piece block having a straight bore circular in cross section extending therewith from its forward face to an end wall at the rear face and a bore of reduced diameter through the 45 wall coaxial with the first bore, a plunger slidable longitudinally in the bores and having a forward portion fitting the larger bore and a rear portion fitting the smaller bore, the forward portion of the plunger having a key slot longitudinally therein, a releasable detent extending into the key slot and preventing rotation of the plunger but permitting its movement longitudinally, a scraping tool with a sharp cutting extremity on the forward end of the plunger outside of the 50 bore, resilient means normally forcing the plunger-

3

er forwardly, a support disposed outside of and having an opening therein receiving and closely fitting the block, and a releasable detent carried by the support for engaging and holding the block in place therein.
